DISCHARGE DEVICE

John W. Carlson, Chicago, Ill.

Application November 5, 1946, Serial No. 707,850

6 Claims. (Cl. 138—46)

1

This invention relates in general to flow restrictors or discharge devices which are particularly adapted to restrict the flow of liquids under pressure such as carbonated water.

Devices of this character have been used heretofore for dispensing carbonated liquids in many different places such as soda fountains and vending machines capable of dispensing carbonated beverages. While the discharge device disclosed herein is particularly adapted for use on such a carbonated beverage vending machine, it is by no means limited to such use.

It is the present practice in machines of this character to maintain a volume of saturated or substantially saturated aqueous solution of carbon dioxide to be discharged into a receptacle. This carbonated liquid is maintained at a high pressure and usually a low temperature. One of the problems which is presented in dispensing a carbonated liquid is the necessity of discharging the solution from its high pressure to atmospheric pressure fast enough for practical purposes and yet slow enough to prevent excessive agitation and turbulence which results in a loss of gas from the liquid. Furthermore, fine particles of foreign matter may become deposited in ordinary discharge devices tending to clog the passages and thereby reduce the efficiency thereof.

It is common practice to employ some means for disrupting the impact of the issuing solution. Such means usually includes a stationary member to receive the impact of the solution under pressure which distributes the liquid in a spray. This has been found to be unsatisfactory in actual practice not only because of the high rate of gas loss, but also because the small passage which distributes the solution in a spray has a tendency to become clogged due to the inevitable presence of fine particles of foreign matter. Such clogging necessitates removal of the device for cleaning.

In my present invention I have been able to overcome the various disadvantages mentioned above by providing a structure which will not only retain a high gas content in the issuing solution but which also will be self-cleaning, thereby avoiding any necessity for complete removal of the device due to clogging.

One of the principal objects of the present invention is to provide a discharge device for restricting the flow of a fluid under pressure, such as carbonated water, which will minimize gas loss and which has self-cleaning characteristics.

Another object is to provide a flow restrictor for discharging fluids such as carbonated water

2

wherein the impact member against which the fluid flows is movable.

A further object is to provide a flow restrictor for discharging fluids such as carbonated water wherein the impact member against which the fluid flows is movable under the pressure of the fluid to form a restricted opening which is self-cleaning and which effectively reduces the velocity of flow without an undue agitation or turbulence thereof.

Still another object is to provide a flow restrictor for discharging fluids such as carbonated water wherein the impact member against which the fluid flows is movable under the pressure of the fluid to form a restricted opening, whereby the initial discharge of fluid will have a cleaning effect thereon before the opening becomes fully restricted.

Another object is to provide a carbonated liquid discharge device wherein a body having an inlet and an outlet therein contains two members, one of which is stationary and one of which is movable, the movable member being movable under fluid pressure toward the stationary member to thereby restrict the passage therebetween after the initial onrush or surge of fluid has had a cleaning effect on the passage.

Other objects and advantages of the invention will become apparent upon reading the following description taken in connection with the accompanying drawings in which:

Fig. 1 is a vertical longitudinal section through the discharge device wherein the passage between the two members is in its normally open position;

Fig. 2 is a view similar to Fig. 1 showing the impact member in its closed position wherein the passage is restricted;

Fig. 3 is a horizontal transverse section taken substantially along the plane of line 3—3 of Fig. 1;

Fig. 4 is a horizontal transverse section taken substantially along the plane of line 4—4 of Fig. 1; and

Fig. 5 is a horizontal transverse section taken substantially along the plane of line 5—5 of Fig. 1.

This invention is a modified form from that disclosed in the co-pending application of Ernest L. Wolf, Ser. No. 700,602, filed October 2, 1946, and comprises a body having an inlet and an outlet therein, which body is hollow and contains a movable impact member having a frusto-conical cavity therein within which the frusto-conical portion of a stationary member extends. The two members are normally spaced apart to provide a passage through which the liquid under pressure is adapted to flow whereby the initial surge will flow

through the passage unrestricted for cleaning purposes, after which the pressure of the liquid will move the impact member toward the stationary member a limited distance to thereby restrict the passage and the further flow of liquid therethrough.

Referring now more particularly to the drawing, the body portion is preferably provided in two sections, the upper section designated by the numeral 2 and the lower section indicated at 4, for ease in assembly. One of these sections is internally threaded at one end thereof and the other is externally threaded to thereby provide a threaded connection 6 therebetween.

The portion 2 of the body is provided with a smaller threaded section 8 at one end thereof for connection with a source of liquid under pressure, which section has a passage 10 therethrough to permit the liquid under pressure to flow within the body. The upper section 2 is tubular and the lower section 4 extends downwardly and is tapered as at 12, terminating in the outlet 14.

A stationary member 16 having an upwardly extending frusto-conical portion 18 is located within the body and has a downwardly extending frusto-conical portion 20. Near the lower end of the tapered portion 12 of the lower section 4, I provide a plurality of radially extending supporting ribs 22 providing passages 24 therebetween for liquid flow. A stationary member 26 of inverted conical shape is adapted to rest on the inner edges of the ribs 22 and thus provide a stationary support for the member 16.

A movable impact member 28 is located in the upper part of the body and has a centrally located downwardly extending opening 30 therein in alignment with the inlet 10 so that fluid entering the inlet will be directed through the passage or opening 30. A frusto-conical cavity 32 is located within the impact member 28 and within which the frusto-conical portion 18 of the stationary member 16 extends in normally spaced relation to thereby provide a passage 34 between the two members.

The member 28 has a tight fit within the body and at its upper end is provided with a sealing ring 36 in order to prevent any of the liquid under pressure from passing between the member and the body. A shoulder is provided adjacent the upper end of the opening 30 and is adapted to support a ring or spider 38 which has a downwardly extending internally threaded tubular member 40 secured thereto and which extends into the opening 30. A plunger 42 has a smaller threaded end 44 adapted to be threadedly engaged with the inner surface of the downwardly extending member 40, which plunger extends downwardly into a central opening extending lengthwise through the stationary member 16.

A stop member 46 extends upwardly into the central opening through the stationary member 16 from the other end thereof and has a head 48 thereon threadedly engaging an enlarged portion of the central opening for purposes of adjustment. The stop member 46 is of a smaller diameter than the central opening through the stationary member and thus provided an annular opening within which a coiled compression spring 50 is located. The upper end of the spring 50 normally bears against the lower end of the plunger 42 thus holding the impact member 28 in its upper position as shown in Fig. 1. When the impact member is moved downwardly, it will strike the end of the stop member 46 and thus limit

the closing movement thereof in restricting the passage 34.

The operation of the device is as follows:

The device is normally in the position shown in Fig. 1 and when a liquid under pressure such as carbonated water enters the inlet 10, it will first pass inwardly through the opening 30 and along the passage 34 to the outlet 14. The initial surge or onrush of the liquid will have a cleaning effect on the passage and flush out any foreign matter which may be present therein. Immediately after this initial surge, however, the force of the liquid against the upper end of the plunger will move the impact member 28 downwardly to its position as shown in Fig. 2, where the bottom of the plunger will contact the upper end of the stop member 46, thereby providing a restricted passage 34 as shown in Fig. 2. This will permit the liquid to be ejected through the outlet 14 with a minimum loss of gas.

If for any reason it is desired to adjust the distance through which the impact member 28 moves, this may be done in a simple and efficient manner by regulating the stop member 46 through its threaded connection with the stationary member.

From the foregoing description it will be evident that I have provided a novel flow restrictor or discharge device particularly useful in the dispensing of carbonated fluids from a vending machine or other dispensing apparatus, which device is self-cleaning, thus avoiding the necessity for frequent disassembly of the device by a service man.

It will be evident that changes may be made in the form, construction and arrangement of parts from those disclosed herein without departing in any way from the spirit of the invention or sacrificing any of the attendant advantages thereof provided, however, that such changes fall within the scope of the claims appended hereto.

Having thus described my invention what I claim as new and desire to secure by Letters Patent of the United States is:

1. A carbonated liquid discharge device comprising a body having an inlet and an outlet, an impact member having a frusto-conical cavity therein movably mounted within said body, and a stationary member having a frusto-conical portion extending within said cavity and normally spaced therefrom to provide a passage for liquid flow from said inlet to said outlet, said impact member being movable under liquid pressure from the inlet toward said stationary member to thereby partially close said passage and restrict the flow of liquid therethrough.

2. A carbonated liquid discharge device comprising a body having an inlet and an outlet, an impact member having a frusto-conical cavity therein movably mounted within said body, a stationary member having a frusto-conical portion extending within said cavity and normally spaced therefrom to provide a passage for liquid flow from said inlet to said outlet, said impact member being movable under liquid pressure from the inlet toward said stationary member to thereby partially close said passage and restrict the flow of liquid therethrough, and adjustable means to limit the closing movement of said impact member.

3. A carbonated liquid discharge device comprising a body having an inlet and an outlet, an impact member having a frusto-conical cavity therein movably mounted within said

body, a stationary member having a frusto-conical portion extending within said cavity and normally spaced therefrom to provide a passage for liquid flow from said inlet to said outlet, said impact member being movable under liquid pressure from the inlet toward said stationary member to thereby partially close said passage and restrict the flow of liquid therethrough, and means to limit the closing movement of said impact member.

4. A carbonated liquid discharge device comprising a body having an inlet and an outlet, an impact member having a frusto-conical cavity therein mounted within said body for longitudinal movement therein, a stationary member having a frusto-conical portion extending within said cavity and normally spaced therefrom to provide a passage for liquid flow from said inlet to said outlet, and yieldable means normally maintaining said members in spaced relation, whereby the initial onrush of liquid under pressure from said inlet will flow through said passage unrestricted to thereby clean the passage, after which said impact member will move toward said stationary member under liquid pressure to thereby partially close said passage and restrict further flow of liquid.

5. A carbonated liquid discharge device comprising a body having an inlet and an outlet, an impact member having a frusto-conical cavity therein mounted within said body for longitudinal movement therein, a stationary member having a frusto-conical portion extending within said cavity and normally spaced therefrom to provide a passage for liquid flow from said inlet to said outlet, said impact member being movable under liquid pressure from the inlet toward said stationary member to thereby partially close said passage and restrict the flow

of liquid therethrough, an elongated opening through said stationary member, a plunger connected to said impact member and extending into said opening, and an adjustable stop member within said opening against which said plunger is adapted to bear to thereby limit the closing movement of said impact member.

6. A carbonated liquid discharge device comprising a body having an inlet and an outlet, an impact member having a frusto-conical cavity therein mounted for longitudinal movement within said body, a stationary member having a frusto-conical portion extending within said cavity and normally spaced therefrom to provide a passage for liquid flow from said inlet to said outlet, said impact member being movable under liquid pressure toward said stationary member to thereby partially close said passage and restrict the flow of liquid therethrough, an elongated opening through said stationary member, a plunger connected to said impact member and extending into said opening from one end thereof, and an adjustable stop member extending into said opening from the other end thereof against which said plunger is adapted to bear to thereby limit the closing movement of said impact member.

Patent No. 2,517,083

JOHN W. CARLSON

It is hereby certified that error appears in the printed specification of the above numbered patent requiring correction as follows:

Column 5, line 10, after the word "member" and before the period, insert *to prevent complete closure of said passage*;
and that the said Letters Patent should be read as corrected above, so that the same may conform to the record of the case in the Patent Office.

Signed and sealed this 7th day of November, A. D. 1950.
